DESIGN FOR A TIE RACK

Clare R. Woodbury, East Orange, N. J.

Application June 16, 1948, Serial No. 147,009

Term of patent 14 years

(Cl. D33—8)

To all whom it may concern:

Be it known that I, Clare R. Woodbury, a citizen of the United States, and a resident of East Orange, county of Essex and State of New Jersey, have invented a new, original, and ornamental Design for a Tie Rack, of which the following is a specification, reference being had to the accompanying drawing, forming a part thereof.

Figure 1 is a view in front elevation of the tie rack; and

Figure 2 is a view in side elevation of the tie rack.

I claim:

The ornamental design for a tie rack, as shown.

CLARE R. WOODBURY.
